DESIGN FOR A DISPLAY RACK

Emanuel Goldenberg, New York, N. Y.

Application January 26, 1934, Serial No. 50,517

Term of patent 3½ years

To all whom it may concern:

Be it known that I, EMANUEL GOLDENBERG, a citizen of the United States of America, residing at 498 Seventh Avenue, in the county of New York and State of New York, have invented a new, original, and ornamental Design for a Display Rack, of which the following is a specification, wherein

Figure 1 is a front perspective view of the display rack showing my new design.

Figure 2 is an end perspective view showing the interior of the display rack.

I claim:

The ornamental design for a display rack, substantially as shown and described.

EMANUEL GOLDENBERG.
